UNITED STATES PATENT OFFICE.

NILS PAUL REHNQVIST, OF NORRKOPING, SWEDEN.

PARALLEL RULER.

Application filed March 12, 1923, Serial No. 624,310, and in Sweden March 14, 1922.

This invention relates to an arrangement of parallel rulers to make possible an alternate movement of the two single rulers in relation to each other so that one of the rulers during the ruling may be moved stepwise after the other over the surface on which the lines are to be drawn in order to use the parallel ruler for double and column ruling etc., whereby the length of the steps 10 determines the distance between the lines.

A parallel ruler according to this invention is shown in the accompanying drawing, Fig. 1 shows a plan view and Fig. 2 an end view, whereas Figs. 3-5 are sections on the 15 lines A—A, B—B and C—C respectively of Fig. 1 the sections being seen in the directions of the arrows.

The two single rulers 1, 2 are movably attached to each other by means of links 3 in 20 the shape of pairs of scissors arranged in longitudinal grooves in the rulers 1 and 2 respectively. The arrangement of these links naturally makes it possible to move the rulers towards and away from each other 25 parallel with themselves and the ruler 2 is normally held in close proximity to the ruler 1 by means of the retractile springs 15 connected to the links 3, as will be later described.

30 In column ruling it is necessary for the attainment of swiftness and precision in the work that one of the single rulers may be moved stepwise after the other whereby the steps are given a definitely fixed length so that either all the steps becomes the same length or that the steps are arranged in groups, which between themselves are exactly equal, but in which groups the steps have different lengths in order to attain suitable 35 different widths of for example the dollar-, cent- and date columns. The following arrangement shows a parallel ruler for accomplishing this purpose.

40 In a plate 5 fastened to the ruler 1 are made grooves 6 running in the crosswise or transverse direction of the ruler and at the side of each groove is a scale graduated in m. m. or in any other suitable unit of measure. In the groove 6 runs the free upturned 45 end of an arm 7 the opposite end of which is formed into a slide 8, which is slidable in the crosswise or transverse direction of the ruler in guiding grooves 9 in a plate 10 on the opposite ruler 2. The movement of the 50 slide in one direction is limited by a wall 11.

For the adjustment of the rulers 1 and 2

relative to each other along the scale, the arm 7 may be formed into or provided with an index movable along the scale. It is however more suitable to arrange in the groove 60 6 a movable shoulder or stop member 12 for the arm, as shown in the drawing, which shoulder by means of a screw 13 and a nut 14 may be fastened in any place in the groove. By means of this shoulder, with 65 which the bent up part of the arm 7 is adapted to cooperate, is fixed the length of the movement of the arm 7 respective of the ruler 2. The parallel ruler is used in the following manner.

70 After one line is drawn by means of the ruler 1 said ruler is held firmly in its position while the operator with one finger presses against the turned up end of one of the arms 7 and thereby pushes the other 75 ruler 2 away from the first one against the tension of the springs 15 and as far as the shoulder 12 associated with said arm permits, which shoulder 12 by means of the scale is adjusted in advance for a certain 80 column width. Afterwards the ruler 1 is pushed beside the other ruler and a new line is drawn. If the distance between said line and the following line be unchanged the ruler 2 is again moved by the same arm. If 85 on the contrary the distance is to be altered the ruler 2 is moved by a different arm 7 the shoulder 12 of which is adjusted for a longer movement of the arm counted from its initial position. The new movement can 90 take place without hindrance from the first used arm 7 since the ruler has a movement relative to said arm. The length of the second movement obviously corresponds with the difference between the distances of 95 the two shoulders from the zero graduations. If the rulers are to be moved a third step of a different length from the two previous lengths the third arm 7 with the shoulder 12 adjusted after the new distance is used. In 100 Fig. 1 the parallel ruler is arranged for two column widths. It is evident that the ruler may be provided with any other number of grooves, arms 7 and shoulders 12 according to the number of column widths to be used. 105 In order to make the ruler 1 move automatically toward the ruler 2 and normally maintaining said rulers in close proximity, there is arranged between the respective slide 4 and the opposite end wall in the groove 110 in which said slide is mounted, the retractile spring 15 previously referred to. The

springs may also be arranged directly between the two rulers 1 and 2.

As may be understood by the foregoing, the essential feature according to this invention is the arrangement to make possible a stepwise movement of one of the single rulers in relation to the other and a changing of the length of the steps. It is evident that the arrangement may be altered in many ways within the scope of the invention to attain the above mentioned purpose.

Having now described my invention, what I claim as new and desire to secure by Letters Patent is:—

1. An instrument of the character described, including parallel rulers, means for connecting the same to permit of transverse movements relative to each other, a plate carried by one of said rulers and having a plurality of slots therein, and sliding members carried by the other ruler capable of moving the latter ruler relative to the first named ruler, and having portions engage-

able and movable in the slots of said plate respectively and forming finger grips for 25 said members.

2. An instrument of the character described, including parallel rulers, means for connecting the same to permit of transverse movements relative to each other, a plate 30 carried by one of said rulers and having a plurality of slots therein, sliding members carried by the other ruler capable of moving the latter ruler relative to the first named ruler, and having portions engageable and movable in the slots of said plate 35 respectively and forming finger grips for said members, and a stop member adjustable longitudinally of each of said slots and engageable by the portion of the sliding member movable in the associated slot to limit the movement of said member when the same is caused to move said other ruler.

In witness whereof, I have hereunto signed my name.

NILS PAUL REHNQVIST.
